UNITED STATES PATENT OFFICE.

LORRAINE Q. WILSON, OF BALTIMORE, MARYLAND.

ARCH-SUPPORTING INSOLE.

Application filed February 13, 1923. Serial No. 618,796.

To all whom it may concern:

Be it known that I, LORRAINE Q. WILSON, a citizen of the United States, residing at Baltimore, State of Maryland, have invented certain new and useful Improvements in Arch-Supporting Insoles; and I do hereby declare the following to be a full, clear, and exact description of the invention, such as will enable others skilled in the art to which it appertains to make and use the same.

This invention relates to new and useful improvements in orthopedic appliances and particularly to devices for use in the treatment of fallen arches.

One object of the invention is to provide a device of this character which is simple in construction, and which is durable and effective in its operation.

Another object is to provide an insole for a shoe wherein the metallic arch supporter is replaceable by others of different sizes, and having different arcs.

Another object is to provide a device of this character wherein the metallic arch member is spring pressed, so that upon applying springs of different lengths and strengths, the metallic arch member may be made to support persons of different weights.

A further object is to provide a device of this character wherein the metallic arch is readily removable, and wherein the spring is also removable, with novel means for retaining the spring in proper engagement with the metallic arch member.

Other objects and advantages will be apparent from the following description when taken in connection with the accompanying drawing.

In the drawing:

Figure 1 is a plan view of an insole equipped with the arch supporter.

Figure 2 is a bottom plan view of the insole, showing the means for retaining the spring in place.

Figure 3 is an enlarged transverse sectional view on the line 3-3 of Figure 2.

Figure 4 is a longitudinal section on the line 4-4 of Figure 2.

Referring particularly to the accompanying drawing, 10 represents an insole formed from leather, or other suitable material, and which is arranged to be placed within a shoe.

Secured to the upper face of the insole, and covering the intermediate portion of said face, is a sheet 11, of leather, rubber, or

other suitable material which will yield or stretch to a degree sufficient for the successful operation of the invention. In the intermediate portion of the insole there is formed an opening 12, through which projects the lug 13 of the metallic arch supporting plate 14, said plate being slipped between the upper face of the insole and the sheet 11, as seen in the sectional views of the drawing.

Secured to the lower face of the insole, and extending longitudinally of the intermediate portion thereof, is a metal plate 15, the portion which crosses the opening 12 being formed with an opening 16 registering with

the opening 12, and also partially receiving the lug 13 therein. It will be noted that the lug 13 is of smaller diameter than the openings of the insole and of the plate 15, and removably engaged on the lug is a coil

spring 17, of the required tension and strength, said spring being snugly seated within the openings of the insole and of the plate. Formed on the plate 15, and extending at right angles from the side of the apertured portion thereof, is a lateral bracing arm 18, the portions of the plate which extend longitudinally of the insole, and from the opposite sides of the opening 16

serving as braces to hold the intermediate portion of the insole longitudinally. Pivotally connected to one of the longitudinal portions of the plate 15, adjacent the central opening 16, is an arm 19, the free end of

which has the notch or recess 20 in one side for engagement with the headed stud 21 extending from the lower face of the plate 15, at the opposite side of the opening 16, as

clearly seen in Figure 2.

Thus, when a spring is properly seated in the opening 16, and encircles the lug 13, and the pivoted arm 19 swung across the lower end of the spring with its notch receiving the headed stud 21, the spring will be tensioned to urge the plate 14 upwardly against

the sheet 11. The arch of the foot of the wearer is disposed on this sheet, and the weight of the person causes a slight depression of the spring. The spring is of sufficient strength to yield to a slight degree, but readily supports or presses upwardly the arch of the foot of the wearer, with the result that the muscles of the arch, and of the entire foot, are relieved of the strain incident to the ailment known as "fallen arch."

Attention is called to the fact that the arch supporting plate 14 may be readily re-

ferred to the accompanying drawing, 10 represents an insole formed from leather, or other suitable material, and which is arranged to be placed within a shoe.

Secured to the upper face of the insole, and covering the intermediate portion of said face, is a sheet 11, of leather, rubber, or

5 moved and another plate of larger or smaller size substituted, the sheet of leather or rubber 11 being unattached along the inner edge of the intermediate portion thereof.

10 5 Thus, the sheet 11 and the portion of the insole covered thereby forms a pocket for the reception of the plates 14 of different sizes. The lug of any one of the plates 14, which might be used, will be disposed in the same position relative to the edges of the plate so that it will readily enter the opening 12, for receiving the spring thereon.

15 What is claimed is:

1. An arch supporter including a base having an aperture, a flexible retaining means on the upper side of the base, a rigid arch supporting member removably disposed between the base and the flexible retaining means and engaging in said aperture, and means releasably supported within said aperture and engaging the supporting member for urging said member upwardly into distending relation to the flexible means.

2. An arch supporter including an apertured base, a flexible retaining means on the upper face of the base, a rigid arch supporting member disposed between the flexible means and the base and having a lug disposed in the aperture of the base, a resilient means in the aperture engaging with the lug for urging the arch supporting member upwardly against the flexible means, and means on the lower face of the base for releasably retaining the resilient means within said aperture.

3. An arch supporter including an insole having an opening in its intermediate portion, an apertured bracing plate on the lower face of the insole and having its aperture registering with the opening of the in-

sole, an arch supporting plate disposed on the upper face of the insole and having a lug disposed in the opening thereof, a coil spring within the brace aperture and encircling the said lug, and a movable means on the lower face of the insole for releasably retaining the spring in position to urge the plate upwardly, and a flexible retaining means on the upper face of the insole against which the said plate presses.

4. An arch supporter including a base, a removable arch supporting plate on the base, a retaining means on the base engaged and flexed by the said plate, means on the plate for engagement with the base, and resilient means on the base for urging the said plate into arch supporting position.

5. An arch supporter including a base, a flexible retaining means on the base, a removable rigid arch supporting means disposed between the flexing means and the base and interlockingly engaged with the base, and a resilient means removably carried by the base for urging the flexible means and arch supporting means into arch supporting position.

6. An arch supporter including a base having an aperture, a flexible retaining means on the upper side of the base, a rigid arch supporting member removably disposed between the base and the flexible retaining means and engaging in said aperture, resilient means supported within said aperture and engaging the supporting member for urging said member upwardly into distending relation to the flexible means, and means movable across said aperture for releasably holding the resilient means within the aperture.

70 In testimony whereof, I affix my signature.

75 80 LORRAINE Q. WILSON.
